UNITED STATES PATENT OFFICE

2,546,623

DRAWSTRING BAG MANUFACTURE

Julius Abler, Los Angeles, Calif., assignor of one-half to Abel Engelman, Chicago, Ill.

Application September 29, 1948, Serial No. 51,809

7 Claims. (Cl. 150—11)

1

My invention relates to the manufacture of drawstring bags.

Generally speaking, the manufacture of drawstring bags heretofore has entailed a substantial amount of hand labor, particularly with respect to the placement and arrangement of the drawstring in proper position in the hem adjacent the mouth of the bag. While suggestions have heretofore been made for the placement or insertion of the drawstring in the hem by various mechanical means, none of them, so far as I am aware, has adequately met the problem. Such mechanisms or procedures which have heretofore been proposed have been characterized by relatively great complexity and expense or they have not proven satisfactory in actual practice. Typical of previously suggested practices are those disclosed in U. S. Patents Nos. 1,861,864; 1,920,822; 1,920,823 and 1,920,824.

I have evolved a new and highly advantageous method for manufacturing drawstring bags which is simple to carry out, utilizes existing and standard sewing mechanisms, and enables the production of such bags to be accomplished in large quantities per unit of time and with little manual labor.

In general, in accordance with my invention a row of relatively closely spaced ravelable loops of string is formed in a web of fabric or other suitable material, most desirably near an edge of said web, the material is then folded over adjacent said row of loops to form a hem, and the hem is sewed whereby to leave said row of loops protruding outside said hem with the connecting portions of string forming said loops being inside said hem. The material is then cut into the desired lengths for making said bags and, due to the relatively close spacing of the loops, each of such lengths has a substantial number of said loops. The sewing of the bags is then completed in accordance with usual practice as, for example, by sewing along the appropriate edges of the material. This may be done by overcasting procedures or, alternatively, by sewing with chain or lock stitch machines and then turning the bags rightside out. At this stage, by pulling on the free ends of the string forming the loops, the loops are unravelled or straightened, the string forming the same becomes enclosed within the hem, and the extra length of string resulting from straightening said loops extends outside the bag.

I have found it to be especially advantageous to form the ravelable loops by using standard or conventional sewing machines modified only

2

to the extent that, in use, instead of forming a complete stitch, only a ravelable loop is formed. This may readily be accomplished in an ordinary chain stitch sewing machine, for example, a "Union Special" machine of this type, by eliminating the string from the looper. In certain lock stitch sewing machines, such as certain "Singer" machines, the result is achieved by eliminating the bobbin string. In an overcasting machine, as, for example, a "Merrow" or "Union Special" overcaster, the result is obtained by eliminating the string from the loopers. I prefer to use the single needle chain stitch sewing machine, modified in use as described above.

15 The invention will be clearly understood in the light of the drawings and the accompanying description wherein:

Fig. 1 shows a piece of bag fabric before any sewing operations have been performed thereon;

20 Fig. 2 shows a piece of the bag fabric after the initial sewing operation, the spaced loops of string shown protruding from one side of the fabric near an edge thereof;

25 Fig. 3 shows the reverse side of the fabric of Fig. 2;

30 Fig. 4 shows the piece of bag fabric after the second sewing operation wherein a part of the fabric is bent back to form a hem and the hem is sewed, the spaced loops of string appearing preferably at or close to the edge;

Fig. 5 shows a finished drawstring bag in open position but prior to the operation of pulling the loops through the hem;

35 Fig. 6 shows the finished drawstring bag in open position but after the loops have been unravelled or straightened by being pulled through the hem;

40 Fig. 7 is a side elevational view showing, fragmentarily, one conventional type of single needle chain stitch sewing machine which has been modified only to the extent that, in use, the looper string or loop-forming mechanism string is not utilized;

45 Fig. 8 is a horizontal sectional view taken along the line 8—8 of Fig. 7 looking in the direction of the arrows;

50 Figs. 9 and 10 are fragmentary views, partly in section, showing different positions of the sewing mechanism of Fig. 7 for forming the incomplete stitches in the form of ravelable loops of string;

Fig. 11 is a side elevational view showing, fragmentarily, a different type of sewing machine, namely, a lock stitch machine which has been

modified only to the extent that the bobbin string is not utilized; and

Fig. 12 is an enlarged view showing the formation of the loops of string.

A drawstring bag, at various stages of its production pursuant to the present invention, is shown more particularly in Figs. 1 to 6, inclusive.

Numeral 1 is a piece of fabric before any operations have been performed thereon and may comprise ordinary bag making fabrics or suitable types of paper or the like. The initial sewing operation serves to form a row of ravelable loop portions of string 2, preferably near an edge 3 of the fabric. The loop portions 2 comprise closely spaced loops proper 4 protruding on one side of the fabric and connected to each other on the other side of the fabric by connecting portions 6 of said string. At this stage, it is clear that the loops of string may be unravelled and removed from the fabric simply by pulling on an end thereof. Numeral 7 shows the hem, which is formed by turning down or folding over the material adjacent the row of loops and sewing the same by stitching 8, leaving the loops proper 4 protruding outside the hem and near the edge of the hemmed material with the connecting portions 6 now inside the hem. As I have stated above, the loops 4 are, in general, relatively closely spaced. In the usual case, from about 3 to about 8 of such loops per linear inch is satisfactory and, in most instances, I find that from 5 to 7 loops per linear inch gives excellent results.

After the operations have been performed as described above so as to convert the fabric to the form shown in Fig. 4, the web of fabric is cut and sewed in accordance with conventional practices to form the bag 13. This may be done by folding the fabric and sewing the two open sides or, as shown, by sewing along the side edges 9 and 11 and the bottom 12. The two free ends 14 and 16 of the loops 4 are then grasped by the fingers and pulled with the result that the loops are unravelled or straightened, the string which formed the loops becomes enclosed within the hem, and the extra length of string resulting from straightening said loops extends outside the hem. It will be noted that, as the loops 4 are unravelled or straightened and the string passes into the hem, a double row of apertures 17 and 18 is left in the fabric. These apertures 17 and 18, through which the string of the loops 4 originally passed, are not substantially larger than double the diameter of the string.

In Figs. 7 to 12, inclusive, I show conventional sewing machines which may be utilized in forming the ravelable loops 4 of string in the web of fabric. Since such sewing machines are well known in the art, I have shown them only fragmentarily.

Referring to Figs. 7 to 10, inclusive, there is shown a single needle chain stitch machine of the type known in the trade as a "Union Special" machine. It includes, mounted upon a frame, a rocker arm 21 which supports a feed dog 22 operated through a cam 23, a looper arm 24 carrying a looper 25, all below the throat plate 26. Mounted above the throat plate is the usual presser foot shaft 27 which carries the presser foot 28, and the needle shaft 29 which carries the needle 31. By eliminating the string from the looper, and utilizing the string only on the needle, it will be seen that the effect of the sewing operation on a piece of fabric is to form incomplete chain stitches in the form of ravelable loops. In

Figs. 9 and 10, two different positions of the needle 31 and looper 25 are shown, the needle being left unthreaded only for purposes of clarity of illustration, Fig. 10 showing the manner in which the looper functions to catch the needle thread and form the loops which are ravelable only because the looper is not threaded.

In Fig. 11, wherein a fragmentary view of a certain "Singer" single needle lock stitch machine is shown, there is the throat plate 35, the feed dog 36, the presser foot 37, needle 38, bobbin case 39 and bobbin 41. As previously stated, when such a machine is used, the bobbin thread or string is eliminated, only the needle string being used.

It will be understood, of course, that while, in general, it is highly advisable to utilize existing types of sewing machines, any other machines which function to produce a row of ravelable loops in a fabric material or the like may be employed in the practice of my method and for the production of drawstring bags and blanks and fabric strips for use in the production of complete drawstring bags.

In the commercial practice of the invention, it is advantageous to practice the invention by continuously feeding a web of fabric material or the like through the sewing machine or other ravelable loop-forming device and, thereafter, continuously folding the material adjacent the row of loops to form the hem. This may be done in various ways as, for example, by alining the loop-forming machine with the hemming machine so that immediately upon the formation of the row of loops the hemming is effected. It is also advantageous to set up the equipment so that, after the hemming operation, the cutting of the material into the desired lengths for the making of the bags can be carried out mechanically and in a continuous operation.

While I have described my invention in detail, it will be understood that no unnecessary limitations should be read thereinto, the scope of the invention being pointed out in the appended claims.

What I claim as new and desire to protect by Letters Patent of the United States is:

1. In a method of manufacturing drawstring bags, the steps which comprise, forming in a web of material near an edge thereof a row of connected ravelable loops of string spaced so closely that a plurality of such ravelable loops are present in a single bag blank, folding said material adjacent said row of ravelable loops to form a hem and sewing said hem whereby to leave said row of ravelable loops protruding outside said hem with the connecting portions of string forming said ravelable loops inside the hem.

2. In a method of manufacturing drawstring bags, the steps which comprise, forming in a web of material near an edge thereof a row of connected ravelable loops of string spaced so closely that a plurality of such ravelable loops

are present in a single bag blank, folding said material adjacent said row of ravelable loops to form a hem, sewing said hem whereby to leave said row of ravelable loops protruding outside said hem with the connecting portions of string forming said ravelable loops inside the hem.

3. In a method of manufacturing drawstring bags, the steps which comprise, forming in a web of material near an edge thereof a row of connected ravelable loops of string spaced so closely that a plurality of such ravelable loops are present in a single bag blank, folding said material adjacent said row of ravelable loops to form a hem, sewing said hem whereby to leave said row of ravelable loops protruding outside said hem with the connecting portions of string forming said ravelable loops inside the hem, cutting said material into bag blanks, each having a plurality of ravelable loops, and sewing the bag blank along appropriate edges for completing the bag.

3. In a method of manufacturing drawstring

bags, the steps which comprise, forming in a web of material near an edge thereof a row of connected ravelable loops of string spaced so closely that a plurality of such ravelable loops are present in a single bag blank, folding said material adjacent said row of ravelable loops to form a hem, sewing said hem whereby to leave said row of ravelable loops protruding outside said hem with the connecting portions of string forming said ravelable loops inside the hem, cutting said material into bag blanks, each having a plurality of ravelable loops, sewing the bag blank along appropriate edges for completing the bag, and pulling on the ends of the string forming the ravelable loops whereby the loops are unraveled or straightened, the string forming the same becomes enclosed within the hem and the extra length of string resulting from straightening the ravelable loops extends outside of the bag.

4. In a method of manufacturing drawstring bags, the steps which comprise, forming in a web of material near an edge thereof a row of connected ravelable loops of string spaced about 3 to 8 of such ravelable loops per lineal inch so that a plurality of such ravelable loops are present in a single bag blank, folding said material adjacent said row of ravelable loops to form a hem and sewing said hem whereby to leave said row of ravelable loops protruding outside said hem with the connecting portions of string forming said ravelable loops inside the hem.

5. A fabric bag provided with a hem at its top and a row of connected ravelable loops of string protruding outside of the hem with the connecting portions of the string forming said ravelable loops inside the hem, said ravelable loops being adapted to be unraveled or straightened by pulling on the ends of the string whereby said string becomes enclosed in said hem and the extra length of string resulting from straightening said ravelable loops extends outside of the hem.

6. An article adapted to be formed into draw-

string bags comprising, a web of fabric having a hem along an edge thereof and adapted to be cut into bag blanks, and a row of connected ravelable loops of string protruding outside of the hem near the edge of said hemmed fabric with the connecting portions of the string forming said ravelable loops being inside the hem, and ravelable loops being so closely spaced that a plurality of such ravelable loops are present in a single bag blank, and said ravelable loops being adapted to be unraveled or straightened by pulling on the ends of the string whereby said string becomes enclosed in said hem and the extra length of string resulting from straightening said ravelable loops extends outside of the hem.

7. A bag blank for making a draw string bag comprising a fabric blank having a hem along an edge thereof and adapted to be sewed into a bag, and a row of connected ravelable loops of string protruding outside of the hem near the edge of the hemmed blank with the connecting portions of the string forming said ravelable loops inside the hem, and said ravelable loops being adapted to be unraveled or straightened by pulling on the ends of the string whereby said string becomes enclosed in said hem and the extra length of string resulting from straightening said ravelable loops extends outside of the hem.
